UNITED STATES PATENT OFFICE

2,417,605

TURRET LOCKING MECHANISM

Carrell E. Miller, Windsor, Vt., assignor to Cone
Automatic Machine Company Inc., Windsor,
Vt., a corporation of Vermont

Application October 27, 1944, Serial No. 560,691

1 Claim. (Cl. 29—37)

1

This invention relates to locking mechanism for indexing turrets, such for example, as those employed for carrying the work holding spindles of multiple spindle lathes and screw machines, though the invention in its broader aspects is not restricted thereto. Such turrets, particularly in multiple spindle lathes and screw machines of the larger sizes, are of considerable weight, and their inertia forces during indexing correspondingly large. Secure locking of such turrets between indexing operations has heretofore resulted in considerable shock and noise, and efforts to lessen these objections have usually resulted in a less secure locking action.

The present invention has for an object, therefore, to decrease the noise and shock of the locking action, while at the same time to insure that this locking action is secure. To these ends, the locking mechanism, in accordance with the present invention, is snapped to an initial locking position under a relatively light spring action, thus reducing the noise and shock, and it is immediately thereafter forced under increased yielding pressure into full locking position and there held until such time as it is desired to unlock the turret for indexing. The increased pressure may be provided by loading the spring or springs by which the initial locking action is produced and the unlocking may be so accomplished as to remove the heavy locking pressure suddenly, producing an initial loosening shock to the locking mechanism and thereafter to fully release the locking mechanism against relatively light spring pressure.

For a more complete understanding of this invention, reference may be had to the accompanying drawings in which

Figure 1 is a fragmentary transverse vertical sectional view on line 1—1 of Figure 2 of a multiple spindle lathe of the well known Cone type, embodying the invention, and showing the turret in locked position.

Figure 2 is a detail sectional view on line 2—2 of Figure 1.

Figure 3 is a top plan view of the locking spring loading device, its actuating cam being shown in section.

For the purpose of illustration, this invention is shown as applied to a multiple spindle lathe such as is illustrated in the Cone Patent No. 2,142,557. Such a machine includes a turret 1 carrying a plurality of work holding spindles indicated diagrammatically at 2 and indexable about a horizontal axis at 3. At points spaced angularly about the periphery of the indexing

5 turret, are sockets, one of these being shown at 4 in Figure 1, into which may be projected a locking bolt 5 when any of these sockets comes into alignment with the locking bolt, the bolt then being projected into the socket and locking the turret against further indexing action until such time as the bolt is retracted, whereupon indexing may be resumed.

10 The locking bolt 5 is slidably guided between ways 6 for motion toward and from the periphery of the turret, and as shown the bolt has a beveled face 7 at its locking end to facilitate the entrance and withdrawal of the bolt from locking position. The bolt is normally pressed toward the periphery of the turret 1 so that it is in position to snap into a locking socket at the end of an indexing operation, and for this purpose it is shown as acted upon by spring means comprising a pair of coil springs 10 reacting between an abutment plate 11 engaging the top end of the locking bolt 5 and an abutment plate 12 engaging the opposite ends of these springs. The plate 12 is guided for motion lengthwise of a pair of guide rods 13 which extend through the 15 coil springs 10 and into the plate 11, and a pair of check nuts 14 threaded on the upper ends of the rods 13 limit the extent of motion of the plate 12 away from the plate 11 in a direction to lighten the pressure with which the springs 10 act upon the locking bolt.

15 Means are provided for releasing the bolt from the turret for each indexing operation, and as shown this means comprises a cam 15 secured to a cam shaft 16 arranged horizontally and passing between the springs 10 and parallel to the indexing turret axis 3. This cam 15 bears against a follower 18 on a lever 17 which is fulcrumed at 19 to a portion 19 of the machine frame. The inner end of the arm 17 is provided 20 with a finger portion 20 which engages in a slot 21 in the outer face of the bolt 5. The cam 15 is so shaped that in certain angular positions of the cam shaft 16 it depresses the outer end of the arm 17, lifting its inner end and retracting the locking bolt therewith.

25 Manually operated means may also be provided for releasing the locking bolt whenever this is desired. As shown this comprises a second cam 22 fulcrumed on the shaft 16 and provided with an actuating handle 23, as shown more particularly in the Cone Patent No. 2,142,557 to which reference has already been made.

When the turret reaches an index position, the bolt 5 is immediately snapped into one of the locking sockets 4 by the action of the springs 10, but

at this time the springs 10 exert a relatively light force only thereon, since the plate 12 is then spaced a substantial distance from the plate 11. Immediately after this initial locking action has been produced, in accordance with this invention, the pressure exerted by the springs 10 is much increased, this being done by loading these springs by exerting downward pressure on the plate 12. For this purpose there bears against the upper face of the plate 12, a loading element comprising a bolt 25 adjustably threaded into an arm 26, this arm being fulcrumed on a cross pin 27 in a bracket 28 secured to the upper face of the frame portion 19 through which the cam shaft 16 extends and in which the shaft has a bearing in the bushing 30. The free end of the arm 26 is downwardly turned, and supports on a pivot pin 31, a cam follower roll 32. This cam follower roll 32 rides against the face of an internal cam 33 secured to the end face of a cam drum 34 carried by the cam shaft 16. The inner face of the cam 33 is so shaped that just after the locking bolt has been projected by the unloaded springs 10, the gradual incline 36 of the cam 33 engaging the follower roll 32, depresses this roll, consequently depressing the spring abutment plate 12 and applying a load to this spring. The cam follower roll 32 then continues to ride along a concentric surface portion 37 of the cam 33, retaining the increased load on the springs, thus holding the locking bolt firmly in locking position against the heavy spring pressure. Just before the locking bolt is to be released, however, a sudden drop-off surface 38 of the cam 33 comes opposite to the cam roll 32, this suddenly allowing the roll to rise and release the loading. The sudden release of this loading causes the springs 10 to react suddenly with a shock which tends to jar the locking bolt 5 loose from the socket in case it should have become stuck therein during the locking action, so that when thereafter the cam 15 actuates the lock release lever, the locking bolt may be readily retracted out of locking position and release the turret for indexing. The loading pressure is put on thereafter only after the locking bolt has been projected for initially locking

the turret at the end of the next indexing operation.

From the foregoing description of an embodiment of this invention, it should be evident to those skilled in the art that various changes and modifications might be made without departing from the spirit or scope of this invention.

I claim:

In combination, a turret indexable about an 10 axis and having angularly spaced sockets in its periphery, a locking bolt slidably guided for motion toward and from said periphery in position to be projected into said sockets serially and lock said turret in indexed positions, a pair of laterally 15 spaced coil springs operatively bearing at one end against said bolt and tending to project said bolt, an abutment bearing against the opposite ends of said springs, means supporting said abutment for motion toward and from one end of each 20 of said springs to thereby load and release load from said springs, a rotary shaft extending through the space between said springs, cam means actuated by said shaft for retracting said bolt against the pressure of said springs to release said turret for indexing and for permitting 25 said springs to project said bolt to lock said turret when one of said sockets comes into registry with said bolt, a cam follower, a member carrying said follower and engaging said spring abutment, and 30 an internal cam carried by said shaft cooperating with said follower and shaped to move said follower toward said one spring end to load said springs when said bolt is in projected turret locking position and to release such load when said bolt is about to be retracted.
